COMBINED HAIR DRYER AND STYLING
ATTACHMENT THEREFOR

John L. Benty, Maplewood, and Daniel Friedman, Edison, N.J., assignors to Clairol Incorporated, New York, N.Y.

Filed Oct. 12, 1971, Ser. No. 188,400

Term of patent 14 years

Int. Cl. D28—03

U.S. Cl. D86—10 F

Fig. 1

Fig. 2

Fig. 3

Fig. 4

Fig. 5

Fig. 6

FIG. 1 is a perspective view of a combined hair dryer and styling attachment therefor showing our new design;

FIG. 2 is a perspective view of a hair dryer, with the styling attachment removed for convenience of illustration, showing our new design;

FIG. 3 is a top plan view of FIG. 2;

FIG. 4 is a front view thereof;

FIG. 5 is a left end view;

FIG. 6 is a right end view; and

FIG. 7 is a bottom plan view.

We claim:

The ornamental design for a combined hair dryer and styling attachment therefor, substantially as shown and described.
